FIG. 1

FIG. 2.

Harry D. Wood
Inventor

By *Geo. P. Kimmel*

Attorney

UNITED STATES PATENT OFFICE.

HARRY D. WOOD, OF FAIRMOUNT, INDIANA.

STATIONERY APPLIANCE.

1,287,554.

Specification of Letters Patent. Patented Dec. 10, 1918.

Application filed November 19, 1917. Serial No. 202,770.

To all whom it may concern:

Be it known that I, HARRY D. WOOD, a citizen of the United States, residing at Fairmount, in the county of Grant and State 5 of Indiana, have invented certain new and useful Improvements in Stationery Appliances, of which the following is a specification.

This invention relates to stationery appliances and it is the principal object of the invention to provide an improved pen or pencil support adapted to be engaged with and supported upon the neck of an ink bottle or well and serving as means for receiving 15 the pen or pencil and maintaining the same in a convenient position to the user.

Among other aims and objects of the invention may be recited, the provision of a device of the character mentioned with a 20 view to compactness, and in which the number of parts are few, the construction simple, the cost of production small, and efficiency and operation high.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the same.

In the drawings:—

Figure 1 is a side elevation of the device in use, and

Fig. 2 is a perspective of the same.

Referring more specifically to the drawings, wherein like reference characters designate corresponding parts in the several views, 1 represents the body of the improved support, the same being semi-circular in cross section and having a spring clip 2 formed upon the rear wall thereof, said clip being formed by slitting the rear wall of the body and rolling the same upon itself. Lugs 3

are formed upon the forward wall and one 45 end of the rear wall of the support body and, obviously, serve as means for retaining a pen or pencil in the semi-circular support and lessening liability of accidental displacement of the same. 50

If desired, a spring clip 4 may be secured to or formed integral with the forward wall of the body of the support, thus, affording means for engaging and positively retaining an article upon the same until removed by 55 a user.

From the foregoing, it will be readily understood that I have provided an exceedingly simple and efficient pen or pencil support and further, a device which may be 60 easily engaged with the neck of the conventional design of ink bottle or well without injuring or altering the same in any way. Further, the device due to its simplified construction, may be manufactured at a mini- 65 mum cost.

Manifestly, the construction shown is capable of considerable modification and such modification as is within the scope of my claims, I consider within the spirit of my 70 invention.

I claim:—

1. A support of the character described including a body portion having a spring arm struck from one side wall thereof at a 75 point above its bottom and a rearwardly disposed spring finger formed integral with and extending from the marginal portion of the opposite side wall of said body.

2. A support of the character described 80 including a substantially trough-like body portion having one side wall thereof split longitudinally for a portion of its length and bent rearwardly to provide a spring arm. 85

In testimony whereof, I affix my signature hereto.

HARRY D. WOOD.
